SAMUEL N. SENNA, OF HOLYOKE, MASSACHUSETTS, ASSIGNOR OF ONE-HALF TO
CHARLES E. TORRANCE, OF HOLYOKE, MASSACHUSETTS.

TENSILE-STRENGTH TESTER.

1,173,612.

Specification of Letters Patent. Patented Feb. 29, 1916.

Application filed December 5, 1914. Serial No. 875,719.

To all whom it may concern:

Be it known that I, SAMUEL N. SENNA, a citizen of the United States of America, residing at Holyoke, in the county of Hampden and State of Massachusetts, have invented a new and useful Tensile-Strength Tester, of which the following is a specification.

My invention relates to improvements in machines for testing the tensile strength of various thin materials, such as paper and other fabrics, leathers, celluloid, and the like, and resides in certain peculiar resilient clamping means, piston-driven hydraulic rupturing means, in connection with which is used a rubber diaphragm of the old Muller tester type, and operating mechanism for said clamping and rupturing means, together with such auxiliary and subsidiary parts and members as may be required or desired in order to make the tester complete and serviceable, all as hereinafter set forth.

The objects of my invention are, first, to provide a hydraulic tester, having a rubber diaphragm, with powerful, uniformly-increasing-pressure clamping means for the sample while being tested; second, to furnish a tester with means to secure the sample before the actual test is made, and with means for making the test, by puncturing the sample or causing it to be punctured, after said sample is secured; third, to provide constant-speed and easily controllable driving means for the reciprocable parts, and, fourth, to produce a strong and durable tester that is comparatively simple in construction and operation, accurate, and withal entirely practicable and efficient.

Heretofore much trouble has been experienced with the common type of testers, because of the insufficient or inefficient clamping means for the sample, with which such machines are equipped, and it has been my aim, successfully achieved, entirely to eliminate any trouble of this nature from the present tester.

Speed and clamping variations are the most common sources of inaccuracy in a tester of the class herein referred to, but with my machine these sources of inaccuracy are entirely eliminated.

Other objects and advantages will appear in the course of the following description.

I attain the objects and secure the advan-

tages of my invention by the means illustrated in the accompanying drawings, in which—

Figure 1 is a longitudinal central vertical section through a tester which embodies a practical form of my invention, the motor and its support being shown in elevation, and, Fig. 2, a detail of parts of the cam shaft and clutch-operating mechanism.

Similar numerals refer to similar parts throughout the several views.

In the form of the tester illustrated in connection herewith, a supporting frame 1 is provided, said frame being mounted on a bed plate 2, and, since I prefer to employ an electric motor with which to operate the tester mechanism, I have represented the same at 3, and shown it mounted on a support 4, which latter is also mounted on said plate. In order to obtain strength and rigidity in the frame 1 at the testing point, I prefer to make said frame at one end, the front end, of the punch type. This is done by cutting out the frame 1 at 5 and thus forming a head 6 above and a foot or base 7 below. The recess 5 also affords a clear space for the work. At the top of the frame 1 are two bearings 8 for a horizontal shaft 9. Within the frame is a horizontal fluid chamber 10 which opens at one end into a vertical cylinder 11 located in the approximate center of said frame and opening through the top thereof, and at the other end through the top of the base 7. An opening 12 is formed in the front end of the frame 1 and communicates with the adjacent end of the chamber 10. The opening or passage 12 is for a gage with which the bursting pressure in pounds per square inch is registered, such gage being attached at the outer end of said passage. This gage is not shown because it is old and well known in the art and forms no part of the present invention. The chamber 10 is designed to contain a quantity of liquid or fluid preferably glycerin. A piston 13 is provided to operate in the cylinder 11, and said cylinder may be lined with a brass bushing 14 for the purpose of preventing said piston from sticking.

The motor 3 has a shaft 15 which extends beneath the rear terminal portion of the shaft 9 and at right-angles thereto. Secured on the motor shaft 15 is a worm 16. Inter-

meshing with the worm 16 is a worm-gear 17 which is loosely mounted on the shaft 9 behind the vertical plane of the rear end of the frame 1. A bracket 18 extends rearwardly from the back end of the frame 1, and a housing 19, for the worm 16, is secured to said bracket. Rising from the housing 19 is a gear-case 20 for the worm-gear 17. The housing and gear-case are of usual construction, being made in sections which are bolted or screwed together.

Before proceeding to describe in further detail the driving mechanism of the tester, of which the worm 16 and the worm-gear 17 are essential parts, I will take up the other elements.

A platform or table 21 has a stem 22 which is screwed or otherwise securely and firmly fastened to or in the base 7, and a vertical passage 23 extends clear through said table and stem, such passage opening at the bottom into the front end of the chamber 10. The circular area of the passage 23 is usually equal to one square inch. Placed on the table 21 over the top of the passage 23 is a rubber diaphragm 24, a plate 25 and a nut 26 being employed to hold said diaphragm securely and prevent displacement thereof. A pin 27 is set in the top of the table 21, beyond the edge of the diaphragm 24, and projects into the plate 25 to prevent the same from turning while the nut 26 is being screwed into place on said table or removed therefrom. The nut 26, which is angular in cross-sections as shown, is adapted to fit over the outer rim or edge of the plate 25, when said plate is in place on the table 21 with the diaphragm between said table and said plate, and to be screwed onto the said table, the latter having an externally threaded part for that purpose. There is a central opening 28 in the plate 25, which opening is directly over the passage 23, with the diaphragm 24 between, and 45 of the same diameter as that of said passage.

The diaphragm 24 is released by simply unscrewing the nut 26 and taking off the plate 25, and the same or another diaphragm is secured in place with equal facility, as will be readily understood. Since the diaphragm is itself liable to rupture while in the act of making a test by rupturing a sample on the table, it is desirable to have convenient holding and releasing means for the diaphragm, so that a ruptured or defective diaphragm can be easily and quickly replaced with a perfect one. A packing-ring 29 is inserted between the base 7 and the table 21 to insure a tight joint at that place.

60 The piston 13 may be hollow, and it is packed at the base, to prevent leakage, by means of a cup-packing 30 held in place by a screw 31 tapped into the bottom of said piston. At the top of the piston 13, 65 above the cylinder 11, is a yoke 32 which is

equipped with an anti-friction roller or follower 33. Secured on the shaft 9 above the follower 33 is an eccentric or cam 34. A spring 35 encircles the piston 13, between the top of the cylinder 11 and the yoke 32, 70 and tends always to force said piston upward and to retain the follower 33 in contact with the cam 34. By means of the cam 34 and with the assistance of the spring 35 the piston is reciprocated. A pin 36 extends 75 from the piston 13 into a vertical slot 37 in the bushing 14, and moves up and down in said slot as said piston reciprocates, the purpose of said pin being to prevent the parts from turning and so throwing the follower 80 33 out of its proper relation to the cam 34.

In reciprocating, the plunger 13 at each downward stroke acts on the fluid in the chamber 10 and the passage 23, tends to compress the same, and forces it upward in 85 said passage against the underside of the diaphragm 24, with the result that said diaphragm is expanded upwardly into and through the opening 28 in the clamping plate 25, and it is this action that ruptures 90 a sample held on the table 21, or rather on said plate which is the sample-receiving part of the table. The aforesaid operation, with the result produced thereby, in so far at least as the action of the fluid on the diaphragm is concerned, is common to the Mullen and other testers of a similar type, so also is the registration by the gage hereinbefore mentioned of the pressure required to rupture the sample, so that nothing further need be said concerning the same.

The head 6 is bored vertically, the upper and major portion of the bore being enlarged to form a chamber 38. A hollow plunger 39, is provided to reciprocate in and through the constricted or smaller bored part of the head 6, and has an external flange 40 at the top, which flange has a sliding fit in the chamber 38. Screwed on or otherwise fastened to the plunger 39, below the head 6, is a tripod 41 which carries at the bottom a circular plate or clamp 42. Since the axial center of the plunger 39 is directly over the axial center of the table 21, the clamp 42 is located directly over or above said table. The clamp 42 has a central opening 43 therein to accommodate the diaphragm 24 when expanded and the portion of the sample that is ruptured or tested, said clamp then being down on the plate 25, as will presently appear. A spring 44 encircles that portion of the plunger 39 that is in the chamber 38, between the bottom of said chamber and the flange 40, and tends to force upwardly said plunger with the tripod 41 and clamp 42.

Arranged to reciprocate vertically in the plunger 39 is a solid plunger or rod 45. This rod has a yoke 46 at the top, which yoke is equipped with an anti-friction roller 130

or follower 47. A shoulder 48 at the base of the yoke 46 operates in the upper part of the chamber 38 and has a sliding fit therein to steady the rod 45. A heavy calibrated 5 spiral spring 49 is located in the chamber 38 between the top of the plunger 39 and the shoulder 48, and the rod 45 with the yoke 46 and follower 47 is supported at all times by said spring. Normally the spring 49 is in 10 its approximately fully expanded condition or inert. This spring is of such capacity as to insure an adequate clamping pressure, which is always uniform, before the actual test begins, as will be made plain hereafter.

15 An eccentric or cam 50 is secured on the front terminal of the shaft 9, which terminal projects over the head 6, such cam therefore being directly above the follower 47. The follower 47 is retained in constant 20 contact with the cam 50 by means of the spring 44 which is seated on the annular floor of the chamber 38 and acts through the plunger 39 or its flange 40, the spring 49, and the yoke 46. Initially the cam 50 is disposed with its low part in contact with the follower 47. As a means to maintain the follower 47 in its true relation to the cam 50, a lug 51 may be provided on the shoulder 48 and a longitudinal slot 52 in the head 6 25 for said lug. The slot 52 must be long enough to accommodate the travel of the lug 51 as the latter moves with the parts actuated by the cam 50; and the slot 37 also must be of sufficient length to accommodate the 30 travel of the pin 36 as said pin moves with the piston 13. The cam 50 has a throw that is sufficient to insure adequate clamping pressure before the test actually occurs, and the two cams (34 and 50) must be arranged 35 or timed with that end in view. The throw of the cam 34 is sufficient to produce the required amount of action on the part of the fluid in the chamber 10 and under the diaphragm 24. The adjacent surfaces of the 40 clamp 42 and the plate 25 are corrugated to enable them more firmly to grip the sample while the test is being made.

The shaft 9 is held against endwise movement by the bearings 8 and the contiguous 45 cams or cam hubs. A collar 53, which is secured on the shaft 9 immediately back of the gear-case 20, and a collar 54, which is secured on said shaft immediately in front of the hub of the worm-gear 17, prevent said 50 worm-gear from moving axially on said shaft. Extending forward from and integral with the hub of the worm-gear 17 is an annular clutch member 55. Mounted on the shaft 9, in front of the clutch member 55 55 and designed to engage and release the latter, is a hollow clutch member 56. The shaft 9 has a longitudinal passage 57 therein, which opens through the rear end thereof, and said shaft also has oppositely-disposed 60 longitudinal slots in the sides thereof, as 65 represented at 58. The slots 58 are adjacent to the forward end of the clutch member 56, and open into the passage 57. A shipper rod 59 extends into and operates in the passage 57, and also projects from the open end of 70 said passage. On the rear end of the rod 59 is a handle 60. A transverse pin 61 connects the rod 59 with the member 56, such pin passing through the slots 58 and operating therein. The slots 58 must be of sufficient length, as must also the passage 57, to 75 enable the pin 61 to be moved the necessary distance to throw the clutch out and in. A spring 62 is interposed, within the two clutch members, between the collar 54 and 80 the closed end of the member 56, and the tendency of such spring is to force said member 56 away from the member 55. The handle 60 is loosely mounted on the rod 59, but prevented from becoming detached therefrom by a screw 63 which passes through the outer end of said handle into threaded engagement with the adjacent end of said rod. Extending forward from the front end 85 of the handle 60, which end encircles the rod 59, is a pair of fingers 64. The fingers 64 are so proportioned that their front ends may rest on the back end of the shaft 9, when the rod 59 is drawn rearwardly to cause the member 56 to engage the member 55, and 90 so retain said member 56 in engagement with said member 55. Slots are cut in the back end of the shaft 9 to receive the fingers 64, when the member 56 is released to the spring 62, and thus to enable such release to 95 take place, the handle 60 being turned on the rod 59 and the screw 63 at such time in order to move said fingers into line with said slots. One of the aforesaid slots is clearly 100 shown at 65 in Fig. 2. The clutch is represented as being thrown out in Fig. 1, while the clutch-operating members shown in Fig. 2 are disposed in the manner required in order to throw in said clutch.

To throw in the clutch and start the machine, the handle 60 is grasped and moved rearwardly to draw more of the rod 59 from the shaft 9 and force the member 56, through the medium of the pin 61 and against the resiliency of the spring 62, into 105 engagement with the member 55. The pin 61 is now in the rear ends of the slots 58. Assuming that the motor 3 is running and driving the worm-gear 17, through the medium of the shaft 15 and the worm 16, as 110 soon as the clutch is thrown in the shaft 9 with the cams 34 and 50 is set in motion, through the medium of the clutch members and the pin 61 which rotatably connects the member 56 with said shaft, and said shaft 115 continues to revolve until the clutch is again thrown out. The member 56 may be secured or maintained in engagement with the member 55 by releasing the handle 60 120 when the parts are so positioned relatively 125 130

that the fingers 64 engage the extreme end of the shaft 9.

To throw out the clutch and stop the machine, without shutting off the current from the motor, hold or turn the handle 60 in such a way as to cause the fingers 64 to ride into the slots 65. This action releases the member 56 to the spring 62 and the latter actuates said member out of engagement 10 with the member 55, the pin 61 then being moved forward in the slots 58 and the rod 59 being carried farther into the passage 57. The worm-gear 17 only stops when the current is shut off from the motor. The 15 driven parts revolve very slowly owing to the difference in diameter between the worm and worm-gear.

In making a test the sample is placed on the plate 25, while the follower 47 is in contact with the low part of the cam 50, and the clutch is thrown in if not already in. The cam 50 commences to revolve and first forces the clamp 42 down onto the sample and the plate 25, through the medium of the 25 follower 47, the yoke 46 with its shoulder 48, the substantially inert spring 49, and the plunger 39 with the attached tripod 41, and against the resiliency of the spring 44. As the cam 50 continues its revolution and as 30 soon as the clamp 42 meets with the resistance offered by the table 21, the spring 49 is compressed between the shoulder 48 and the plunger 39, the plunger rod 45 descending farther into the plunger 39, with the result that said clamp is forced onto the sample 35 with a great amount of pressure, owing to the strength and power of the spring 49. The sample is now gripped between the clamp 42 and the plate 25 with a force that 40 can not be broken, or from which the sample can not be loosened at any even the most minute point. By this time the cam 34 has rotated sufficiently to begin to depress the follower 33 and with it the plunger 13, 45 against the resiliency of the spring 35. The descending plunger 13 tends to compress or displaces the fluid beneath it and in the chamber 10 and the passage 23 and forces said fluid against the rubber diaphragm 24, thus stretching the latter and forcing it up 50 through the plate opening 28 against the sample over said opening until, while the cam 34 is still rotating and before the high part thereof passes the follower 33, said 55 stretched or expanded diaphragm ruptures said sample. The rupturing of the sample does not take place until the maximum clamping pressure on the sample has been attained; in fact, the diaphragm 25 may 60 not come into contact with the sample until the maximum or approximately maximum clamping pressure is applied to the sample. The diaphragm 24 expands into the recess or opening 43 in the clamp 42, and carries 65 with it the contiguous portion of the sam-

ple. The pressure exerted by the diaphragm to rupture the sample is registered in the usual manner and by the usual means.

When the high part of the cam 50 rides away from the follower 47, the latter rises, 70 first with the plunger rod 45 until the spring 49 expands, and then with said rod and spring and the plunger 39 with the tripod and clamp, the spring 44 carrying up the parts after said spring 49 has become inert 75 or practically so. The clamp is now clear of the table, and the ruptured sample may be removed. By the time the low part of the cam 50 is once more in contact with the follower 47 the members controlled thereby are 80 in initial position and ready for the next cycle. Meanwhile the high part of the cam 34 has ridden away from the follower 33 and the spring 35 has elevated the plunger 13, so that the pressure on the fluid is relieved and the diaphragm 24 permitted to contract and assume its normal condition 85 and position under the opening 28. The mechanism is now ready to make the test on the next sample.

The cam-actuated mechanism may be stopped and started at each cycle or may be permitted to continue in operation during the entire time that the machine is in use 90 for making tests, the stopping and starting in any event being effected by means of the rod 59 and its handle 60. When the machine as a whole is permitted to run continually, the operator has nothing to do, after once starting the cams, but to insert and remove the samples one after another, stopping the mechanism only after the completion 95 of the entire series of tests.

Although I have shown and described one embodiment of my invention, it is to be understood that said invention is not restricted to such embodiment, but is broad and comprehensive enough to include all structures wherein are employed resilient means for producing clamping pressure in combination with means for producing hydraulic pressure, or cam-actuated clamping pressure and hydraulic pressure-producing means, provided such structures come within the scope of my claims.

What I claim as my invention, and desire to secure by Letters Patent, is—

1. A tensile strength tester comprising direct-acting resilient clamping means, means to overcome the resistance offered by said first-mentioned means and to actuate the latter into clamping position, hydraulic pressure-producing means consisting in part of a reciprocable member in parallel relation with said first-mentioned means, a rupturing element in line with the axial center of said clamping means, said rupturing element being operated by said hydraulic pressure-producing means, and means to operate said hydraulic pressure-producing means.

2. A tensile strength tester comprising direct-acting cam-actuated pressure-producing means adapted to produce, under the action of the cam, a clamping effect, cam-actuated hydraulic pressure-producing means consisting in part of a reciprocable member in parallel relation with said first-mentioned means, and a rupturing element operated by said hydraulic pressure-producing means. 5
3. A tensile strength tester comprising direct-acting resilient clamping means, means to overcome the resistance offered by said first-mentioned means and to actuate the latter into clamping position, hydraulic pressure-producing means consisting in part of a reciprocable member in parallel relation with said first-mentioned means, a rupturing element in line with the axial center of said clamping means, said rupturing element being operated by said hydraulic pressure-producing means, and cam mechanism to operate said hydraulic pressure-producing means. 10
4. A tensile strength tester comprising direct-acting resilient clamping means, cam-mechanism adapted to overcome the resistance offered by said first-mentioned means and to actuate the latter into clamping position, hydraulic pressure-producing means consisting in part of a reciprocable member in parallel relation with said first-mentioned means, a rupturing element in line with the axial center of said clamping means, said rupturing element being operated by said hydraulic pressure-producing means, and cam-mechanism for operating said hydraulic pressure-producing means. 15
5. A tensile strength tester comprising direct-acting cam-actuated resilient means adapted to produce, under the action of the cam, a clamping effect, such means consisting in part of spring-pressed telescoping plungers, and cam-actuated hydraulic pressure-producing rupturing means. 20
6. In a tensile strength tester, a supporting member, a fluid chamber opening through said chamber, a yielding diaphragm secured to said member over the opening therein, direct-acting resilient means for holding a sample over said diaphragm, said resilient means consisting in part of spring-pressed telescoping plungers, and the axis of said resilient means being in line with the center of said diaphragm, and operating means adapted to overcome the resistance offered by said resilient means and actuate the latter into clamping position. 25
7. In a tensile strength tester, a supporting member, a fluid chamber opening through said member, a yielding diaphragm secured to said member over the opening therein, direct-acting resilient means for holding a sample over said diaphragm, said resilient means consisting in part of spring-pressed telescoping plungers, and the axis of 30
8. In a tensile strength tester, a supporting member, a fluid chamber opening through said member, a yielding diaphragm secured to said member over the opening therein, direct-acting resilient means for holding a sample over said diaphragm, said resilient means consisting in part of spring-pressed telescoping plungers, and the axis of said resilient means being in line with the center of said diaphragm, and cam-operated means adapted to overcome the resistance offered by said resilient means and actuate the latter into clamping position. 35
9. In a tensile strength tester, a supporting member, a fluid chamber opening through said member, a yielding diaphragm secured to said member over the opening therein, direct-acting resilient means for holding a sample over said diaphragm, said resilient means consisting in part of spring-pressed telescoping plungers, and the axis of said resilient means being in line with the center of said diaphragm, and means for overcoming the resistance offered by said resilient means and operating the latter to produce a uniformly-increasing pressure on said sample. 40
10. In a tensile strength tester, direct-acting resilient pressure-producing clamping means, said means consisting in part of spring-pressed telescoping plungers, hydraulic pressure-producing means consisting in part of a reciprocable member in parallel relation with said first-mentioned means, a puncturing element in line with the axial center of said resilient means, said puncturing element being operated by said hydraulic pressure-producing means, and means to overcome the resistance offered by said resilient means and operate the latter in advance of said puncturing means. 45
11. In a tensile strength tester, a supporting member provided with a yielding diaphragm, a fluid chamber opening through such member to said diaphragm, direct-acting resilient means for holding a sample on said member over said diaphragm, said resilient holding means consisting in part of spring-pressed telescoping plungers, and the axis of said resilient holding means being in line with the center of said diaphragm, pressure-applying means for the fluid in said chamber, said last-mentioned means being in parallel relation with said resilient holding means, means adapted to overcome the resistance offered by said resilient holding means and operate the latter into holding position, and means to operate said pressure-applying means for the fluid. 50
12. In a tensile strength tester, a support- 55
- 60
- 65

ing member provided with a yielding diaphragm, a fluid chamber opening through such member to said diaphragm, direct-acting resilient means for holding a sample on said member over said diaphragm, the axis of said resilient means being in line with the center of said diaphragm, pressure-applying means for the fluid in said chamber, and means adapted first to overcome the resistance offered by said resilient holding means and operate the same into holding position, and then to operate said pressure-applying means for the fluid.

13. In a tensile strength tester, a supporting member provided with a yielding diaphragm, a fluid chamber opening through said member to said diaphragm, direct-acting resilient means for holding a sample on said member over said diaphragm, the axis of said resilient means being in line with the center of said diaphragm, pressure-applying means for the fluid in said chamber, and means automatically to operate said resilient holding means and said pressure-applying means.

14. In a tensile strength tester, a supporting member provided with a yielding diaphragm, a fluid chamber opening through said member to said diaphragm, resilient means for holding a sample on said member over said diaphragm, pressure-applying means for the fluid in said chamber, and automatic means adapted first to operate said holding means and then to operate said pressure-applying means.

15. In a tensile strength tester, a supporting member provided with a yielding diaphragm, a fluid chamber opening through said member to said diaphragm, direct-acting resilient means for holding a sample on said member over said diaphragm, the axis of said resilient means being in line with the center of said diaphragm, pressure-applying means for the fluid in said chamber, and power-driven means to operate said resilient holding means and said pressure-applying means.

16. In a tensile strength tester, a supporting member provided with a yielding diaphragm, a fluid chamber opening through said member to said diaphragm, resilient means for holding a sample on said member over said diaphragm, pressure-applying means for the fluid in said chamber, and power-driven means adapted first to operate said holding means and then to operate said pressure-applying means.

17. In a tensile strength tester, a supporting member provided with a yielding diaphragm, a fluid chamber opening through said member to said diaphragm, direct-acting resilient means for holding a sample on said member over said diaphragm, said resilient means consisting in part of spring-pressed telescoping plungers, and the axis

of said resilient means being in line with the center of said diaphragm, pressure-applying means for the fluid in said chamber, said last-mentioned means consisting in part of a reciprocable member in parallel relation with said resilient means, means for overcoming the resistance offered by said resilient means and operating the same to produce a uniformly-increasing pressure on said sample, and means for operating said pressure-applying means.

18. In a tensile strength tester, a supporting member provided with a yielding diaphragm, a fluid chamber opening through said member to said diaphragm, direct-acting resilient means for holding a sample on said member over said diaphragm, said resilient means consisting in part of spring-pressed telescoping plungers, and the axis of said resilient means being in line with the center of said diaphragm, pressure-applying means for the fluid in said chamber, said last-mentioned means consisting in part of a reciprocable member in parallel relation with said resilient means, means for overcoming the resistance offered by said resilient means and operating the same to produce a uniformly-increasing pressure on said sample, and means for causing said pressure-applying means to operate.

19. A tensile strength tester comprising a supporting member provided with a yielding diaphragm, a fluid chamber opening through said member to said diaphragm, direct-acting resilient clamping means for a sample while being tested, said resilient means consisting in part of spring-pressed telescoping plungers, and the axis of said resilient means being in line with the center of said diaphragm, means adapted to overcome the resistance offered by said resilient means and actuate the same into clamping position, pressure-applying means for the fluid in said chamber, said last-mentioned means consisting in part of a reciprocable member in parallel relation with said resilient clamping means, and means to actuate said pressure-applying means after a predetermined pressure has been exerted on said sample by said clamping means.

20. The combination, in a tensile strength tester, with a supporting member provided with a yielding diaphragm, a fluid chamber opening through said member to said diaphragm, and pressure-applying means for the fluid in said chamber, of reciprocable telescoping members carrying a clamp over said supporting member, a spring adapted to be compressed when said clamp is brought into contact with said supporting member, and means to actuate said telescoping members and compress said spring.

21. The combination, in a tensile strength tester, with a supporting member provided with a yielding diaphragm, a fluid chamber

opening through said member to said diaphragm, and pressure-applying means for the fluid in said chamber, of reciprocable telescoping members provided with a follower at one terminal and carrying a clamp at the other terminal over said supporting member, a spring adapted to be compressed when said clamp is brought into contact with said supporting member, a cam for operating said telescoping members, and a spring arranged to retain said follower in contact with said cam.

22. The combination, in a tensile strength tester, with a supporting member provided with a yielding diaphragm, a fluid chamber opening through said member to said diaphragm, a cylinder communicating with said chamber, a piston in said cylinder, a cam, said piston being provided with a cam-follower, and a spring arranged to retain said follower in contact with said cam, of resilient means to hold a sample on said support over said diaphragm during the action on said sample of said diaphragm while subjected to the fluid under pressure in said chamber from said piston.

23. The combination, in a tensile strength tester, with a supporting member provided with a yielding diaphragm, a fluid chamber opening through said member to said diaphragm, a cylinder communicating with

said chamber, a piston in said cylinder, and means to operate said piston, of reciprocable telescoping members carrying a clamp over said supporting member, a spring adapted to be compressed when said clamp is brought into contact with said supporting member, and means to actuate said telescoping members and compress said spring.

24. The combination, in a tensile strength tester, with a supporting member provided with a yielding diaphragm, a fluid chamber opening through said member to said diaphragm, a cylinder communicating with said chamber, and a cam-actuated piston in said cylinder, of cam-actuated telescoping members carrying a clamp over said supporting member, and a spring adapted to be compressed when said clamp is brought into contact with said supporting member.

25. In a tensile strength tester, a table having a passage therethrough, a rubber diaphragm, a perforated plate, means to prevent said plate from turning on said table, and a nut adapted to be screwed onto said table over the rim of said plate, with said diaphragm between said table and said plate.
